UNITED STATES PATENT OFFICE.

ALBIN P. RISSLER AND WALTER G. HAMILTON, OF CHICAGO, ILLINOIS, ASSIGNEES TO
CHICAGO RAILWAY EQUIPMENT COMPANY, OF CHICAGO, ILLINOIS, A CORPORATION OF ILLINOIS.

REVERSIBLE STRUT FOR BRAKE BEAMS AND METHOD OF MAKING SAME.

Application filed November 7, 1921. Serial No. 513,430.

To all whom it may concern:

Be it known that we, ALBIN P. RISSLER and WALTER G. HAMILTON, citizens of the United States, residing at Chicago, Illinois, have invented a certain new and useful Improvement in Reversible Struts for Brake Beams and Methods of Making Same, of which the following is a full, clear, and exact description, such as will enable others skilled in the art to which it appertains to make and use the same, reference being had to the accompanying drawings, forming part of this application, in which—

Figure 1 is a top plan view of our improved reversible strut for brake beams.

Figure 2 is a side elevational view of the same.

Figure 3 is a detail view of the bent strap from which the strut is formed.

Figure 4 is a detailed view of the bent end of the strut.

Figure 5 is a sectional view on line 5—5 of Figure 4.

Figure 6 is a view of a modified form.

Figure 7 is a sectional view on line 7—7 of Figure 6.

This invention relates to a new and useful improvement in reversible struts for brake beams and method of making the same, the object being to produce a strut from a bent piece of bar or strap iron which as initially formed has a loop or stirrup the spaced legs or jaw of which is designed to receive a casting forming a seat for the tension member, substantially as shown in Hawkins Patent No. 1,387,981, dated August 16, 1921, and the bent end of which may be swedged or turned down so as to be received and secured in position in the channel shaped compression member, also as indicated in said Hawkins patent. The seat for the tension member maintains the strut in position for a right or left hand brake lever, and in the event that it is desired to change from one to the other, it is only necessary to reverse the position of the strut, without dismantling the parts of the beam.

In the drawings, referring to Figure 3, we have shown a stirrup shaped blank having leg members 1 and a connecting member 2. These leg members may be formed with openings for the brake lever pin and other openings at their extremities for securing

devices in the form of a rivet, or rivets, 3^a 55 by means of which the casting 3 constituting the seat for the tension member is secured in position between the free ends of the fulcrum or in the jaw formed by the legs thereof. The closed end of the stirrup 60 shaped blank may be turned down, as indicated in Figure 4, so that it will fit in the channel of the compression member. This turning down of the end of the strut requires no special manipulation, except the 65 operation of the lathe, and the circular surface of the trunnion thus produced enables the strut to be reversed relative to the compression member without affecting the fastening means between the strut and the compression member of the beam; or the closed end of the strut may be swedged, as shown in Figures 6 and 7, to form the trunnion by a pressure which bends the ends of the strap 70 towards each other, as indicated at 1^a in Figure 7, thereby forming a more complete bearing wall.

By forming the reversible strut from a strap or bar of metal bent upon itself and shaping the end to produce a trunnion which 80 can be received in the channel constituting the compression member of the beam, we leave the end wall of the strut of substantially the same thickness as the metal forming the legs of the strut. This end wall is provided with an opening 2^a for the passage 85 of a rivet or other fastening device, and as the space between the legs of the strut continues to be substantially as wide in the trunnion as it is between the legs of the 90 strut, it is obvious that a riveting tool can be inserted in this space in securing the fastening rivet in position; or, an instrument can be introduced to hold the head of the bolt in place, when the nut is being applied thereon.

What we claim is:

1. The method of forming reversible fulcrums or struts for brake beams which consists in doubling a strap or bar of metal 100 upon itself, then shaping the closed end so that it may be rotatably received in a channel compression member, the cross-sectional area of the opening in the trunnion so formed being substantially as large as the 105 cross-sectional area of the opening or space between the legs of the strut, and spacing the ends of the bent blank or legs of the

strut by means of a member which forms a seat for the tension rod of the beam.

2. A reversible strut for brake beams formed from a bent strip or bar of metal, the bent end of which is shaped to form a trunnion designed to be seated in a channel, the opening in the trunnion so formed being substantially as large as the cross-sectional area of the opening or space between the 10 legs of the strut.

3. A reversible strut for brake beams formed of a strap or bar of metal bent upon itself and the ends of whose legs are spaced apart by a seat for the tension member, the 15 closed end of the blank being shaped to form a hollow trunnion open at its inner end, and whose outer end wall is of sub-

stantially the same thickness as the legs of the strut.

4. A reversible strut for brake beams 20 formed of a strip or bar of metal bent upon itself, the bent end being exteriorly shaped to form a trunnion, designed to be seated between the flanges of the compression member of a brake beam and the open ends of 25 said bar being connected by a block which forms a truss rod seat with stops to limit the movement and determine the angular position of the truss rod therein.

In testimony whereof we hereunto affix 30 our signatures this 31st day of October, 1921.

ALBIN P. RISSLER.
WALTER G. HAMILTON.
